Primary Examiner — Rosemary K Tarcza

Assistant Examiner — Sanjeev Paul

(74) Attorney, Agent, or Firm — Blank Rome LLP

CLAIM

The ornamental design for pillow, as shown and described.

DESCRIPTION

FIG. 1 is a top view of the bean pillow of the present invention.

FIG. 2 is a back view of the bean pillow of FIG. 1.

FIG. 3 is a front view of the bean pillow of FIG. 1.

FIG. 4 is a perspective of the bean pillow of FIG. 1.

FIG. 5 is a perspective of the bean pillow of FIG. 1.

FIG. 6 is a perspective of the bean pillow of FIG. 1; and,

FIG. 7 is a side view of the bean pillow of FIG. 1.

The design resides in parts of the article shown in solid lines only. Parts shown in broken lines form no part of the design.

1 Claim, 7 Drawing Sheets
